APPARATUS FOR THE FINAL REFINING OF
BENZOLS WASHED WITH ACID

Emile Augustin Barbet, Paris, France

Application February 4, 1932, Serial No. 590,965
In France February 5, 1931

1 Claim. (Cl. 202—154)

This invention relates to the refining of benzol in order to obtain in a really pure condition benzene, toluene and xylene or solvents.

Actually, the greater portion of the benzol produced is intended to be incorporated with liquid carburetting agents (petroleum spirits or alcohols); this is the so-called "benzol for motors". For this kind of benzol, if the product has been coarsely refined before washing with acid, a real refining is not necessary. It suffices to effect a simple distillation, separating benzol from resinous tar which has been produced by the reaction of sulphuric acid.

The problem of refining in order to obtain the various constituents in a pure condition is quite different. Concerning benzene, it must totally distill within half a degree centigrade, between 80 and 81° C. For toluene, within one degree centigrade. For xylene, there is an allowance of five degrees, for the reason that, in fact, several xylenes exist, which are somewhat different as far as the boiling point is concerned.

Finally, naphtha-solvent is also separated, and then tarry residues which have been formed by 25 polymerization during purification with sulphuric acid.

The continuous rectification of washed benzol is effected in three successive and interconnected plate columns having for function to respectively 30 supply benzene, then toluene, and finally xylene, all of which must satisfy the conditions of reception above mentioned.

But purification may be carried to a further degree, and although this seems to slightly complicate the apparatus, it is quite advantageous to adopt the process thus improved, as extra-purity is obtained without any supplementary expenses either in fuel or in labour. The general operation remains just as easy and the apparatus 40 works in a totally automatic manner and without necessitating any new regulator.

The improvement consists in effecting a double rectification which is carried out without expense by a double action of the steam. This 45 double rectification has been shown in the drawing as being applied to the plate columns, that is to say, B, B' and F, F' for benzene and K for toluene. As far as the column S for xylene and solvent is concerned, as it does not operate really continuously, the double action would be much less easy to control, and in fact, for these products the fractionation is easier and industry is not so exacting concerning their chemical purity.

1.—*Double rectification of benzene*

55 It is effected with double action, in two plate columns BB' and FF', the second column FF' operating under a certain vacuum (absolute tension between $\frac{1}{3}$ and $\frac{1}{2}$ atmosphere) owing to 60 which the boiling point is lowered from 81° C. to

about 50° C. This drop of temperature is utilized as follows:

Benzene vapours from BB' have a temperature of about 81° C. and pass in a first tubular apparatus D arranged at a higher level than the 65 column BB', so that the benzene condensed in D can flow back to the top of the column B'. A valve 3 is arranged above the outlet flask d; the said valve is sufficiently closed so that only a very small proportion of benzene vapours may 70 pass into the cooler D'.

The head products finally issue through d'. A portion of the liquid is admitted in the test gauge b through the pipe 4 and it is sent to a vessel (not shown) containing the "motor benzol"; the complement proceeds to the U-shaped pipe 5 and is thus added to the reflux of D. 75

On one of the plates at the upper part of B is effected at E a partial extraction of the reflux. This extraction is a benzene which would be already sufficiently pure for satisfying the conditions of reception of trade. But it will be rectified a second time in the plate column FF' which will fractionate the last traces of too light products and of too heavy products. 80

The volume of the extraction E is measured in the test gauge E' and the liquid, passing through the U-shaped pipe 6, feeds the column FF'. 85

Boiling is caused to take place in this column FF' through the medium of the tubular apparatus D which acts as second effect heater. For that purpose, the residual liquid from the bottom of F, issuing through the pipe 12, and pumped by I, is delivered, through the pipe 13 and the valve 14, in the base of the tubular apparatus D. On the 95 other hand, the benzene vapours generated at about 50 or even 60° C. in D are conveyed, by the large heat insulated pipe 15, to the base of F.

Everything will take place as if D was directly placed against the base of F, but with this difference that, owing to its location at a high level, the vapours of the primary column B' can, after condensation in D, directly flow back into B'. 100

If D had been placed at the bottom of the secondary column F, according to the standard arrangement, it is the condensation effected in D which it would have been necessary to pump in order to raise it to the top of B'. In one way or the other, the pump compensates the difference of level which had to be created between the first 110 and second effect.

The secondary column FF' first gives off the too light products, owing to the fractionation ensured by the reflux of the condenser G. As usual, the products condensed in G are divided, from 115 the point 7, in two portions: the most important flows to the top of F' through the pipe 10, whilst the other portion, driven along by the steam ejector 8, ensures the necessary fractionation. The mixture of water vapour and of vapour of 120

too light benzene issuing from the ejector is used for heating in A' the supply of washed benzol from the reservoir A, entering the primary column BB' through the cock 1 and pipe 2. The compound liquid condensed in A' passes to the cooler J and from there enters the decanting apparatus J'. The water falls to the bottom of the decanting apparatus and issues through the test gauge 23, whilst the benzol drawn along issues through 10 the test gauge 22.

It is to be understood that instead of creating vacuum by means of an ejector (which appears to be so much the more simple as it is simply necessary to generate a partial vacuum very easy 15 to obtain) use might be made of a vacuum pump of any type.

At the bottom of the secondary rectifying column FF' the residual reflux has retained traces of heavy impurities; it is therefore necessary to 20 provide an issue for a fraction of this liquid, in order to avoid accumulation of impurities. For that purpose, the extraction is effected at a point in the length of the delivery pipe (pipe 13) of the pump I; the volume of this extraction is measured 25 in the test gauge x, and from there, the extracted liquid is conveyed, by the pipe 35, to the primary column BB'.

The extra-pure benzene, which has been subjected to a double rectification and extracted from 30 F', is cooled at H; its volume is controlled by the cock 24, the pump I' sucks it and delivers it, through 25, in the test gauge L.

Double rectification of toluene

35 It is also effected with double action, and exactly according to the same principles as above; the description of this double rectification can therefore be briefly given.

The primary column K is supplied with the 40 totality of the liquid freed from benzol issuing from the bottom of BB', that is to say from its boiler C. The issue of this liquid continuously takes place by overflow (cock 9, pipe 11). This liquid is automatically raised to about the middle 45 portion of the column K by a live steam emulsifying apparatus L.

Boiling in the column K is produced by a boiler M provided with a coil. The toluene vapours rise through the plates, being purified in the refluxes 50 of the two tubular apparatus N and P. The cock 36 arranged above the flask n, allows but a very small proportion of light vapours to pass into P. These light portions issue through the flask p, pipe 16 and test gauge e. The remainder flows 55 down through the pipe 26, mixes with the product condensed in N (pipe 27) and forms the reflux necessary for the refining operation in the primary column K.

At r is effected an extraction of pasteurized 60 toluene which will be used for feeding the secondary rectifying column Q.

N designates a tubular apparatus acting as second effect heater. It receives the heavy residual liquids from the secondary rectifying column Q, issuing through 37, pumped by O and delivered through the pipe 38 terminating in a balanced valve 28.

Q operates under vacuum (absolute tension from $\frac{1}{3}$ to $\frac{1}{2}$ atmosphere). Owing to this vacuum, the slightly impure toluene from the bottom 70 of the secondary column can be raised to boiling point by the toluene vapours at 111° C. of the primary column K, exactly as for benzene.

The vapours at about 80 – 90° C. produced in 75 N, flow down through the pipe 29 for automatical-

ly heating without expense the bottom of the secondary column Q. This time again it is necessary to effect, at a point on the length of the pipe 38, a slight extraction through the test gauge k, which extraction will re-enter the primary 80 column K.

The vapours from the secondary column Q are condensed in the condenser-cooler Y. The non-condensed portion is sucked by the steam ejector 32 (pipe 31) and the mixture of water vapour and toluene, conveyed by the pipe 33 in the tubular apparatus X, is used for effecting a complementary heating at the base of the secondary column Q.

The portion condensed in Y issues through the flask y and flows back through the pipe 30, to the top of the secondary column Q.

As for the tubular apparatus A', at the issue 95 of X (pipe 40), will be arranged a cooler, then a decanting apparatus and two test-gauges, one for water, the other for the head toluene, which will re-enter the primary column K owing to the emulsifying apparatus L, or by any other means.

The extra-pure toluene cooled at R, issues 100 through the test-gauge f.

The liquid of the boiler M, which no longer contains toluene, will finally yield the xylene and naphtha-solvent it still contains. But as this residue still contains a relatively important 105 proportion of tar, resulting from polymerizations effected by sulphuric acid, it would not be easy, in a continuously operating column, to completely free the tar from the totality of the white spirit with which it is still combined. Therefore the 110 column S is discontinuously fed.

The liquid from M passes, through the pipe 34 and cock 18, into the boiler T which is provided with a steam coil, as the other boilers, and also with steam bubbling through pipe U.

As soon as the liquid covers the coil, heating is effected by this coil alone, and the boiler M can continuously empty through its overflow m. Although TS begin to distill, the level gradually rises in T. The rectification takes place 120 owing to the reflux of the condenser V.

The distillate issuing through v is divided in two portions: reflux through the pipe 19, whilst the pipe 20 allows to effect a small extraction of 125 too light impurities through the test-gauge g.

All the head extractions from the three columns are sent into the vessel containing the "motor-benzol". Through s, cooler s' and test gauge h issues commercial xylene, which must boil within a range of five degrees centigrade.

At the test gauge is drawn off (after cooling in a cooler not shown) a relatively heavy naphtha-solvent, the greater part of which boils between 130 and 180° C.

At a certain moment the boiler T is full. The 135 cock 18 is closed and then the residues from M rise by themselves to the reservoir W, where they will accumulate whilst the exhaustion of the boiler T will be terminated.

When it is noticed that there is no outflow 140 from the test gauges g—h—j, the live steam is cut off from the coil and, on the contrary, steam for bubbling purposes is sent, through U, in the boiler T. This steam draws into the column S the naphtha solvents which may subsist. These solvents, mixed with the condensed water, are sent, when issuing from the test gauge, into a decanting apparatus (not shown in the drawing).

When exhaustion is reached, the steam is cut 150

off, and, through the cock *t* and the pipe 21, the tar is discharged into the reservoir Z.

The cock *t* is again closed and as during all this time the reservoir W has filled up, it is possible, by opening 18, to send a new batch in the boiler T, and to begin again another rectification without appreciable loss of time.

It will be understood that, according to commercial requirements, instead of employing the complete apparatus illustrated in the drawing, the double rectification with double action can be used only for benzene, or on the contrary only for toluene, or finally for neither of them.

The process described allows, without any supplementary expense either in fuel or labour, and in a completely automatic manner, to obtain a benzene and a toluene having a chemical purity largely exceeding the tests actually required. The apparatus which has been shown in the drawing by way of example, can obviously receive modifications and even simplifications if it is desired to obtain extra-purity for only one of the two main hydrocarbons: benzene and toluene.

I claim:

25 Apparatus for refining washed benzene comprising a continuous steam heated primary benzene rectifier adapted to operate at atmospheric pressure, a continuous secondary benzene rectifier adapted to operate at sub-atmospheric pressure, 30 a heater condenser communicating with the primary benzene rectifier adapted to heat the residues of the secondary benzene rectifier and also

provide reflux to the primary benzene rectifier, means for feeding the lower part of the secondary benzene rectifier with the vapours of the said residues evolved from the heater condenser thereby heating the said secondary benzene rectifier, means for conveying part of the liquid reflux of the primary benzene rectifier to the secondary rectifier, means for condensing the purified benzene from the secondary benzene rectifier, a continuous steam heated primary toluene rectifier adapted to operate at atmospheric pressure, and a continuous secondary toluene rectifier adapted to operate at sub-atmospheric pressure, means for conveying residue from the primary benzene rectifier to the primary toluene rectifier, a heater condenser communicating with the primary toluene rectifier, adapted to heat residues of the secondary toluene rectifier and provide reflux to the primary toluene rectifier, means for conveying the residue of the secondary toluene rectifier to the said heater condenser, means for conveying the vaporized residues from the heater condenser to the lower part of the secondary toluene rectifier, means for condensing the purified toluene from the secondary toluene rectifier, a steam heated rectifier for the rectification of the xylene and solvent naphtha from the residue of the primary toluene rectifier and means for conveying the said residue to the said steam heated rectifier.
